UNITED STATES PATENT OFFICE.

HERMAN W. ZIEMER, OF ST. BONIFACIUS, MINNESOTA.

ROWING-GEAR FOR BOATS.

1,264,741.

Specification of Letters Patent. Patented Apr. 30, 1918.

Application filed October 12, 1917. Serial No. 196,160.

To all whom it may concern:

Be it known that I, HERMAN W. ZIEMER, a citizen of the United States, residing at St. Bonifacius, in the county of Hennepin, 5 State of Minnesota, have invented a new and useful Rowing-Gear for Boats; and I do hereby declare the following to be a full, clear, and exact description of the invention, such as will enable others skilled in the art 10 to which it appertains to make and use the same.

This invention relates to an improved rowing gear for boats, and one of the objects of the invention is to provide a device of this 15 kind whereby force, convenience, utilization of power, and ease of manipulation in bow facing oars are attained.

A further object of the invention is to provide a bracket plate to be secured on 20 the upper edge of the side of the boat and provided with upstanding bearings in which a tilting member is mounted, and on which tilting member the rowing gear is pivotally mounted, whereby the upstanding bearing 25 will act as limiting stops for the paddle section and the handle section of the rowing gear.

A further object of the invention is to provide a rowing gear comprising a paddle 30 section and a handle section, which are pivotally mounted upon a tilting member, in combination with a link connection between the two sections, thereby creating greater force of power and ease of manipulation in 35 bow facing oars.

In practical fields the details of construction may necessitate alterations falling within the scope of what is claimed.

The invention comprises further features 40 and combination of parts as hereinafter set forth shown in the drawings and claimed.

In the drawings:—

Figure 1 is a view in perspective of the improved rowing gear as applied to the upper 45 edge of the side of a boat.

Fig. 2 is a plan view of the rowing gear.

Fig. 3 is a sectional view on line 3—3 of Fig. 2.

Referring more especially to the drawings 50 1 designates a portion of one of the sides of a boat, and 2 denotes a bracket plate which is secured by screws 3 on the upper edge of the side. The bracket plate is bent at several different points as shown at 4, 5 55 and 6, thereby forming upstanding loop bearings 7, and 8 designates an elongated

rocking or tilting plate, the ends of which are provided with pintles 9 mounted in the adjacent walls of said upstanding bearings. This tilting plate or strap 8 is parallel with 60 the bracket plate 2. The tilting plate 8 is provided with a pair of edgewise bulges 10 and 11, and rising upwardly from the upper faces of said bulged portions 10 and 11 of the tilting plate are pivot pins 12 65 and 13, which, owing to the construction of said bulges 10 and 11, are offset upon opposite sides of the axial alinement of the pintles 9, whereby the tilting member or plate may more readily tilt, when manipulating 70 the rowing gear. The oar rowing gear comprises the paddle section 14 and the handle section 15, which is manually manipulated. The inner end of the paddle section has a rectangular portion 16, which 75 fits and is secured in a socket 17 rectangular in cross section formed by the opposite plates 18, which are secured to the opposite faces of the rectangular end of the paddle section by the bolts or rivets 19. A rivet 80 or the like 20 also secures the rectangular end portion 16 of the paddle section in said socket 17. The upper and lower walls of the socket and the rectangular portion of the paddle section of the rowing gear have 85 registering openings 21, to receive the pivot pin 13. The inner adjacent ends of said plates 18 are provided with laterally extending lugs 22, which are connected by a pin 23. The handle section 15 of the rowing gear has a handle portion 24 and a rectangular end 25, to which a socket 26 is fitted and secured by means of a pivot pin 27. A pair of plates 28 project outwardly 90 from the outer ends of the upper and lower walls of the socket 26, and these plates have laterally extending lugs 29. The plates 28 are secured by a rivet 30 to the upper and lower faces of the outer end of the rectangular portion 25 of the handle section 15, 95 thereby rendering the parts secure. The socket 26 has its upper and lower walls and the rectangular portion 25 of the handle section provided with registering openings 31, to receive the pivot pin 12. By the foregoing structure it is to be noted that the paddle and handle sections 14 and 15 of the rowing gear are pivotally mounted upon the tilting plate or member 8, so that when the handle section is manipulated up and 105 down and oscillated forwardly and rearwardly, an up and down movement is im-

parted to the paddle section, which is also oscillated forwardly and rearwardly opposite to the forward and rear oscillation of the handle section, through the medium of the link 32. A pin 33 is secured in the ends of the lugs 29, and the opposite ends of the link 32 are provided with rolls or sleeves 34, through which the pins 23 and 33 pass respectively, said link thereby connecting the diagonal opposite pairs of lugs 22 and 29. It is to be noted that by means of the upstanding bearings projecting upwardly beyond the tilting plate or member 8, the paddle and handle sections of the rowing gear are limited in their backward and forward oscillating movements, by means of the plates 18 and 28 respectively engaging said bearings. The upper and lower walls of the sockets constitute wearplates to operate with the tiltable plate 8, and as a rule where rivets or pins extend through oar sections of a rowing gear, said sections in time will tend to crack and split. Therefore, by means of the sockets, the oar and handle sections of the rowing gear are reinforced.

The invention having been set forth what is claimed as new and useful is:

In a rowing gear for boats, a bracket

plate secured on the upper edge of the side of the boat, a tiltable plate, said bracket plate having means in which the tiltable plate is mounted, a rowing gear comprising paddle and handle sections pivoted upon the tiltable plate to oscillate at right angles to the tilting action of the tiltable plate, said sections having diagonally oppositely disposed end portions, a link extending obliquely across the tiltable plate and connecting the said diagonally oppositely disposed end portions, whereby as the handle section is oscillated in one direction, the paddle section is oscillated in the opposite direction, said means of the bracket plate comprising upstanding loop bearings having their upper ends projecting beyond the pivotal plate and constituting limiting abutments to be engaged by the respective sections to limit them in their oscillatory movement.

In testimony whereof I have signed my name to this specification in the presence of two subscribing witnesses.

HERMAN W. ZIEMER.
